UNITED STATES PATENT OFFICE.

FRANK F. CHUDOBA, OF GLASTONBURY, CONNECTICUT, ASSIGNOR, BY MESNE ASSIGNMENTS, TO UNITED STATES HAT MACHINERY CORPORATION, OF RICHMOND, VIRGINIA, A CORPORATION OF VIRGINIA.

FELT SHRINKING.

Application filed July 23, 1921. Serial No. 487,141.

To all whom it may concern:

Be it known that I, FRANK F. CHUDOBA, a citizen of the United States, residing in Glastonbury, in the county of Hartford and 5 State of Connecticut, have invented certain new and useful Improvements in Felt Shrinking, of which the following is a specification.

This invention relates to shrinking matted 10 fur fibers to form felt articles.

In making a felt hat, the fur fibers are usually blown upon a large perforated metal cone, where they mat or adhere together 15 slightly, forming a bat. This cone-shaped bat is dipped into hot water, to effect a certain shrinkage thereof, and render the bat strong enough for handling. The bat may then be shrunken to the desired dimensions 20 and solidified into felt of the desired quality and firmness by means of the present improvements.

Heretofore a bat in flat condition, while wet with hot water, has been rolled up in a burlap blanket, and then rolled, squeezed 25 and manipulated, thereby bending the bat locally in various ways, with the effect of causing vermicular movements of the fibers. Such movement of a fiber is always in the same direction, owing to the presence of 30 minute barbs on the fiber, so that the described manipulation has caused the fibers to creep or felt together. Many further operations have also been necessary to finish the shrinking of the bat, and considerable 35 waste of fur fibers has been incurred.

The present improvements may be carried out after the bat has been removed from the cone upon which it was formed, and after it has been immersed in hot water. The bat 40 is opened and placed upon a bed for the purposes of kneading the same, the bed being conical in form and preferably of such proportions that the bat may fit thereupon, so as to be supported everywhere thereby. 45 The bed may form the interior of a cone-shaped bowl or basket, and the bat is placed within said bowl or form to be subjected to the desired manipulation or kneading.

The preferred manner of kneading the 50 bat placed upon such a bed is to subject it to intermittent pneumatic pressure, applied in such a way as to flex the bat repeatedly

to and fro locally throughout its area. To this end, a bulb may be placed within the open bat, while the latter lies in the bowl-like bed or form. The bulb may be of soft rubber, and may be operated by fluid pressure or compressed air. This flexible bulb may fit inside of the bat; and there may be provided upon said basket or other bed numerous knuckles throughout its area. The bulb may then be expanded by compressed air, whereby the bat is flexed upon the knuckles; and then, upon reducing the pressure of the air or fluid within the bulb, the bat may recover its shape. The operation of inflating and deflating may be repeated, the bat meantime being kept moist with hot water until, by means of the vermicular action of the fibers, the bat has shrunken 70 materially and to the desired proportions. The operation is favored by making the knuckles of soft elastic material, such as soft vulcanized rubber, which conduces to the flexing to and fro or kneading of the 75 bat supported thereon. The operation may be quickly and inexpensively performed, and an even felting of the bat may be secured, so that it will attain the desired proportions and have an even thickness 80 throughout, thus conducing to the availability of the finished hat, and avoiding excessive thickness at any place, or over-consumption of fur. No waste is liable to occur through matting together of the bat 85 at fold creases, since no creasing is done; and the necessity is avoided of opening out the flat bat and refolding it along new lines.

In one form of the invention, a conical bed or support may have the knuckles upon 90 its exterior, and the opened-out bat may be set down upon the cone, and then surrounded by a rubber bulb, which may be inclosed in a pneumatic bell or chamber, and compressed intermittently upon the bat to shrink the 95 same.

Other features and advantages will hereinafter appear.

In the accompanying drawings,

Figure 1 is a sectional elevation of a basket form of bed, with a bat therein positioned to be shrunken by a pneumatic interior bulb; said bulb being shown open to a supply of compressed air. 100

Figure 2 is a similar view to Figure 1, showing the shrinking of the bat as having been completed.

Figure 3 is a sectional plan view taken at about the line 3—3 of Figure 1.

Figure 4 shows the pneumatic valve turned to exhaust position.

Figure 5 shows diagrammatically on a larger scale a sectional view of a fragment 10 of the bed, bat, and pneumatic kneading bulb.

Figure 6 is a view similar to Figure 5, but indicating how the bat is locally flexed by reason of fluid pressure within the bulb.

Figure 7 is similar to Figure 1, but shows 15 a form of bulb which is provided with annular ribs, ridges or corrugations, each vertically crinkled. This figure shows the valve in exhaust position.

Figure 8 is a view similar to Figure 7, but showing the bulb expanded with the rib portions thereof pressing the bat into creases or depressions between the rows of knuckles on the bed.

Figure 9 shows the bat placed open-end 25 down upon a conical bed to enclose the same, the whole being arranged within a soft rubber bulb, which, by pneumatic pressure, is compressed upon the bat to knead the same upon a cone or bed; the parts being shown in exhaust positions.

Figure 10 is a view similar to Figure 9, but shows the rubber bulb compressed by air 30 pressure upon the bat, which is pressed upon the ruffles of the conical bat and thereby kneaded.

Referring to Figures 1 to 6, the brim of the bat to be shrunken is indicated at 10, the 40 conical sides at 11, and the top portion at 12. This bat is placed in inverted condition within a bowl or basket-like bed 13, having a conical form similar to that of the bat, and lined by means of a bag 14, preferably of soft vulcanized rubber and having a smooth 45 outer face to fit in the bowl, but provided throughout on its inner face with knuckles 15. These knuckles may be of soft rubber and vulcanized integrally with the bag or lining 14; the latter consisting preferably of two plies, of which one ply 14 is soft rubber, and the other ply 16 is of rubber having a cloth insertion. As illustrated, the bat may rest upon these soft rubber knuckles 15, which may be in the form of similar regular 50 pyramids of low elevation, or any other suitable protuberances whether regular or not. These knuckles form numerous yielding points or supports upon which the bat may be locally flexed or kneaded for effecting the shrinking thereof.

The knuckles, constituting protuberances, may be in the form of annular corrugations, interrupted ridges, or other designs that will hinder the bat from sliding downwardly into the cone during the shrinking operation.

Within the bat extends a bulb 17, preferably of soft vulcanized rubber, which may be inflated for the purpose of squeezing and kneading the bat against the supporting knuckles 15. This bulb may depend from 70 a nipple 18, the mouth of the bulb being secured upon the nipple by wiring 19.

For convenience in inserting and withdrawing the bat, the bowl 13 may be made to drop away from the bulb. For this purpose the bowl may be provided with a supporting bracket 20, carried by a vertical rack 21, the latter being mounted to slide up and down a post or fixture 22. A pinion 23 meshes with the rack, and may be revolved 75 by means of a crank 24, thereby to drop the bowl clear of the bulb 17 and permit a bat to be inserted in the bowl. The crank 24 is then turned to raise the bowl until the brim 25 at the top thereof is arrested by a flange 26 which may be formed upon the nipple 18, and which may be secured by screws 27 to a horizontal cover-plate 28, cast upon an arm 29 bolted at 30 to the upper part of the post 22. The bowl is held in this lifted or working 80 position by means of latches 31, pivoted at 32 to ears provided upon the nipple flange 26, whereby the bowl and nipple may be supported rigidly together during the shrinking operation. The lifting of the 85 bowl brings the bat up so that it surrounds the pendent bulb 17; and the parts are now ready for the shrinking operation. To keep the bat hot and moist during the kneading thereof, hot water may be supplied through 90 a pipe 33, opening into a channel 34 at the top of the structure above the bowl, the water flowing down around the bat to the bottom of the bowl, where there may be provided a waste-pipe 35.

The compressed air may be admitted through the nipple 18, the latter having for this purpose an inlet pipe 36, communicating with a supply 37 of compressed air. In the supply is placed a three-way valve 38, which may comprise a main diametrical passage 39 and a branch port 40. At Figure 1, the main port 39 forms an open communication from the supply 37 to bulb 17, so that the latter is forced outwardly at all 105 points by compressed air, and packed against the bat, forcing the latter into all the creases between the pyramids 15 with which the kneading bowl is lined, so that the bat is forced to have numerous local 110 flections 41, as seen best at Figure 6. The valve may then be brought promptly to exhaust position, as at Figure 4, in which the branch passage 40 forms a communication 115 between the pipe 36 and an exhaust 42, while the supply is closed by the valve, so that the bulb 17 may resume its normal condition, and the bat may recover substantially its 120 normal unflexed condition; the knuckles, which may have been depressed to some ex- 125 130

tent, also recovering their normal condition. This operation of expanding and exhausting the bulb may be repeated at as short intervals as desired, and with the result that 5 the repeated kneading or flexing of the bat shrinks the same until it reaches, for example, the desired size indicated at 43, Figure 2.

The operation may be summarized as follows: The bowl 13 may be moved downwardly on the post 22 by means of the crank 24, driving the cone downwardly by rack and pinion device 21, 23. The bat 11 is then introduced, while compressed air is 10 shut off from the interior of the bulb 17; the bulb, being smaller than the bat, will not touch the bat. Compressed air is then introduced through the supply 37, and through port 39 and pipe 36. By reciprocating the valve 38, the compressed air escapes, and thus there are alternate vibrations produced in the bulb. This causes the bat 11 to be pressed inwardly against the recesses between the knuckles 15, causing 15 the fur to bend over the knuckles, and to shrink rapidly. As the bat is shrinking, its position gradually shifts relatively to the knuckles, so that fresh portions of the bat are pressed upon the several points and are 20 therefore subjected to flexing by the action of the bulb 17, thus promoting vermicular action throughout the bat, which is hence rapidly brought to desired dimensions at 25 43. The movements of the valve 38 may be effected by an arm 44, connected by a pitman 45 to a rotary or other driver, so that the expansion and contraction of the bulb 30 may be made at regular intervals if desired.

At Figures 7 and 8 a surface view of the lower portion of the bat is seen at 11. The bulb 48 is seen contracted or normal at Figure 7, and expanded at Figure 8, and differs from bulb 17 by being formed with horizontal ribs, ridges or beads 49, one below 35 another, extending around the bulb, each rib in position to press the bat down into the space between adjacent horizontal rows of pyramids 15, as at 41, Figure 8. Each of 40 these ribs 49 may have short vertical crinkles 50 all around the bulb. The effect of the ribs 49, especially when finely wrinkled or corrugated vertically, is to improve the kneading action of the bulb upon the 45 bat, or to improve the vermicular action of the fibers and shrink the bat more quickly, solidly and evenly. In other respects Figures 7 and 8 correspond with Figures 1 to 6. The wall of the ribbed bulb 48 may be of 50 uniform thickness, as shown; and, because of the use of the ribs opposite the annular depressions between the circular rows of pyramids (one such row being seen at Figure 3), the wall of the bulb may be made 55 as thick and formed as desired, and may

require less pneumatic pressure to accomplish a given result upon the bat. Moreover, the ribbed bulb, after being fully expanded, as at Figure 8, tends, upon being exhausted, to resume its original condition as at Figure 7, and thereby to withdraw the walls of the bat entirely from the crevices between the pyramids. This may happen because the air between the bat and the bulb is expelled when they are subjected to pressure as at Figure 8; and, upon the compressed air being exhausted, the atmospheric air flowing down along the pyramid surface keeps the bat and bulb pressed together, the wall of the bat tending to adhere to the wall of the bulb, because of the previous expulsion of air from between them. Thus the bat may be kneaded outwardly by compressed air, and then kneaded inwardly by atmospheric air. This tendency of the bat to adhere to the bulb may also be present in the form of the invention seen at Figures 1 to 6; but the presence of the ribs 49 in the bulb at Figures 7 and 8 tends to increase the flexion or kneading of the bat, as compared with the plain bulb seen at Figure 1. This effect is also favored by the crinkles or corrugations 50. The ribbed bulb will require less expansion than the plain bulb of Figure 1, and it will also cause the fur to be bent inwardly into the recesses as shown in Figure 6, more readily than if the bulb were a plain surfaced bulb.

Some of the principles already disclosed may be employed in a manner which, in some respects, is the reverse of that so far described. This is illustrated at Figures 9 and 10. The bed, instead of being an inverted cone 51, as in the previous figures, stands upon a table 52, and the bat to be shrunk is opened and placed down over said cone, substantially fitting the same, as at 53. Both the cone and the bat stand within a conical rubber or other soft bulb 54, within an air-tight or sealed chamber or bell 55. The latter may be of any suitable form, and is illustrated as conical, and it may be cast upon a bracket 56, secured by bolts 57 to the vertical post 22. To support the parts and permit the bat to be dropped upon the cone and removed therefrom, the table 52 may be provided with a vertical rack 58, which may be cast integral with the table and with a strengthening rib 59. This rack may be lowered by means of pinion 23 and crank 24, the cone table 52 dropping therewith until clear of bell 55, so that the bat 53 may be dropped upon the cone. Then the crank 24 is turned to raise the rack, table and cone 51 to the Figure 9 position, the parts being secured together by suitable locks, as, for example, latches 60; and a wide brim 61, formed upon the base of the bulb 54, being clamped between a flange 62 on the bell 55 and a packing ring 63 upon 130

the table 52, so as to render the bell airtight. At Figure 9 the bell is shown as exhausted by means of the valve 38. At Figure 10 the valve 38 is shown as forming a communication through a pipe 65 with the interior of bell 55, so that the compressed air may squeeze the bulb 54 and compress the bat against the cone table or work support 51. The latter may be either smooth, or covered with such pyramids as seen at Figures 1 to 6, or it may have plain horizontal ridges or ripples 66. The cones or work supports may be of hard material, such as wood or metal, or they may be of soft material such as soft rubber, and may be either solid or hollow. When made hollow and of soft rubber, a greater movement or flection of the bat may be secured at each operation of the valve 38.

Upon return of the valve 38 to the exhaust (Figure 9) position, the compressed air escapes, and the rubber bulb 54 tends to resume its normal expanded condition at Figure 9, and the bat tends to resume its normal condition because of atmospheric pressure within the bat; and in this connection a suitable number of vents 67 may be provided to permit air to pass out at Figure 10, and to let the air in again when the compression valve is returned to the exhaust position at Figure 9. During the shrinking operation the bat may be kept hot and wet by scalding water entering through a pipe 68. The water may flow to the top of the conical work support 51, and descend through a waste pipe 69. The mouth of the bulb may be made wider than is shown at Figure 1, so as to permit the insertion therewith of the cone 51 and the work thereon.

In practising the invention in the manner shown in Figure 1, the mouth of the bulb 17 may be made smaller than shown if desired, as it is on the interior of the bowl or conical work bed 13. The bat may be held on the cone at Figures 9 and 10 by other means than by ridges or points, as, for example, by means of air pressure.

Variations may be resorted to within the scope of the invention, and portions of the improvements may be used without others.

Having thus described my invention, I claim:

Having thus described my invention, I claim:

1. A bat-shrinking apparatus comprising

a tapering bed, said bed serving to support

55. the bat, and means fixed by the action of fluid pressure for intermittently applying surface pressure to the bat.

60 2. A bat-shrinking apparatus comprising a bowl in which the bat is placed, an expandible bulb to insert within the bat, and means for expanding the bulb intermittently by means of fluid pressure, to knead the bat.

65 3. A bat-shrinking apparatus comprising a bowl in which the bat is placed, an expan-

sible bulb to insert within the bat, and means for expanding the bulb intermittently by means of fluid pressure, to knead the bat, numerous knuckles being provided upon the inner surface of said bowl.

4. A lining for a work bowl to be used in shrinking felt bats, said lining comprising a bag of soft rubber formed on its inner face with numerous soft rubber knuckles, the latter being arranged close together and comprising approximately the entire area of said inner face. 75

5. A work bowl in which to shrink felt bats, said bowl having a tapering form and lined by means of a bag formed of soft vulcanized rubber provided throughout its inner face with soft rubber knuckles comprising approximately the entire area of said inner face.

inner face. 6. A work bowl in which to shrink felt bats, said bowl having a tapering form and lined by means of a bag formed of soft vulcanized rubber, a soft rubber bulb arranged within the bag, and means for inflating and deflating the bulb repeatedly. 85 90

7. A bat-shrinking apparatus comprising a bowl in which the bat is placed, an expandable bulb to insert within the bowl, and a nipple to which the mouth of the bulb is secured, said nipple having a passage whereby it is connected to a source of compressed air. 95

8. A bat-shrinking apparatus comprising a bowl in which the bat is placed, an expansible bulb to insert within the bat, and means for expanding the bulb intermittently by means of fluid pressure, to knead the bat, means being provided for effecting separation of the work bowl and the bulb to permit the insertion and withdrawal of bats. 100 103

9. A bat-shrinking apparatus comprising a bowl in which the bat is placed, an expandible bulb to insert within the bat, means for expanding the bulb intermittently by means of fluid pressure, to knead the bat, a rack connected to said bowl, and a pinion for operating said rack to carry the bowl away from the bulb. 110

10. A bat-shrinking apparatus comprising a bowl in which the bat is placed, an expandible bulb to insert within the bat, means for expanding the bulb intermittently by means of fluid pressure, to knead the bat, a rack connected to said bowl, a pinion for operating said rack to carry the bowl away from the bulb, a nipple to which the mouth of the bulb is secured, said nipple having a passage whereby it is connected to a source of compressed air, and means extending from the nipple to the bowl for locking the bowl in working position.

11. A bat-shrinking apparatus comprising a bowl in which the bat is placed, an expandable bulb to insert within the bat, and means for expanding the bulb intermittently by 130

- means of fluid pressure, to knead the bat, a hot water supply channel being provided to extend above the bowl.
12. An apparatus for shrinking a bat, consisting in a bowl provided with a multiplicity of irregular points which prevent the bat from twisting or folding upon itself during the shrinking operation, a rubber bulb introduced inside the bowl, and means to expand the rubber bulb and release the pressure in the bulb alternately.
13. An apparatus for shrinking a bat, consisting of a tapering support provided with a multiplicity of supports to prevent the bat from sliding on the support during the shrinking operation, a rubber bulb placed adjacent to the bat, and means to expand and contract the bulb alternately against the bat.
14. An apparatus for shrinking a bat, consisting in means for holding said bat, a rubber bulb placed adjacent to the bat, and means to expand and contract the bulb alternately against and away from the bat.
15. The process of shrinking a bat, comprising supporting it upon a tapering bed, and repeatedly subjecting said bat to successive compressed air induced kneadings while the bat is hot and moist.
16. The process of shrinking a bat, comprising supporting it upon a tapering bed provided with yielding knuckles throughout its working surface, and repeatedly subjecting said bat to successive compressed air induced kneadings while the bat is hot and moist.
17. The process of shrinking a bat, comprising placing the bat within a bowl having numerous knuckles upon its inner surface, and repeatedly kneading the bat by expanding a bulb therein by means of fluid under pressure.
18. The process of shrinking a bat, comprising placing the bat within a bowl, inserting a bulb within the bat, and alternately admitting compressed air to a bulb and exhausting it therefrom.
19. The process of shrinking a bat, comprising placing the bat within a bowl having numerous soft vulcanized rubber knuckles upon its inner surface, and repeatedly kneading the bat by expanding a bulb therein by means of fluid under pressure.
20. The process of shrinking a conical bat, comprising confining it in open condition between inner and outer conical members, and repeatedly kneading it while confined by the use of compressed air in a soft rubber bulb, which expands to press the bat against soft rubber knuckles provided upon one of said confining members.
21. A bat-shrinking apparatus comprising a bowl in which the bat is placed, an expandible bulb to insert within the bat, said bulb being formed of soft rubber and connected to a supply of compressed air for expanding the bulb, said rubber bulb being formed with horizontal ribs, one below another, extending around the bulb.
22. A bat-shrinking apparatus comprising a bed in the form of a bowl in which the bat is placed, an expandible bulb to insert within the bat, said bulb being formed of soft rubber and connected to a supply of compressed air for expanding the bulb, numerous knuckles being provided upon the working surface of said bed, said rubber bulb being formed with horizontal ribs, one below another, extending around the bulb, each rib in position to press the bat down in the space between adjacent horizontal ripples upon the bed.
23. A bat-shrinking apparatus comprising a bowl in which the bat is placed, an expandible bulb to insert within the bat, said bulb being formed of soft rubber and connected to a supply of compressed air for expanding the bulb, said rubber bulb being formed with horizontal ribs, one below another, extending around the bulb, each of said ribs having numerous vertical crinkles all around the bulb.
24. The process of shrinking a bat, which consists in holding said bat upon a support by means to prevent the bat from twisting or folding upon itself during the shrinking operation, and alternately expanding and contracting a rubber bulb against the bat, to cause it to shrink.
25. The process of shrinking a bat, which consists in holding said bat upon a support, said support being provided with a multiplicity of knuckles, and then alternately expanding and contracting an elastic rubber bulb against the bat to cause the bat to shrink.
26. The process of shrinking felt, consisting in kneading it by means of compressed air acting to vibrate a flexible diaphragm upon the felt while it is supported upon a bed.

FRANK F. CHUDOBA.
